UNITED STATES PATENT OFFICE.

GEORGE SEXTON BENNETT, OF SAN FRANCISCO, CALIFORNIA.

SANITARY DEVICE FOR TELEPHONE-MOUTHPIECES.

1,047,120.

Specification of Letters Patent.

Patented Dec. 10, 1912.

Application filed January 16, 1911. Serial No. 602,919.

To all whom it may concern:

Be it known that I, GEORGE SEXTON BENNETT, a citizen of the United States, residing at San Francisco, in the county of San Francisco and State of California, have invented a new and useful Sanitary Device for Telephone-Mouthpieces, of which the following is a specification in such full and clear terms as will enable those skilled in the art to construct and use the same.

This invention relates to a sanitary appliance for telephones, and its object is to prevent the soiling of the telephone mouthpiece when speaking into the same.

Another object of the invention is to prevent the use of the telephone without changing the paper used to protect the mouthpiece.

Another object of the invention is to provide a device which will automatically prevent the user from speaking into the telephone without first setting the apparatus to shift the covering of the mouthpiece and to automatically shift said covering when the receiver is hung up.

It will be understood by those familiar with telephones that it is common to provide a hook upon which the receiver is placed when the telephone is not in use. Upon most of the standard telephones this hook has come to be a fork upon which the receiver is placed, with the ear-piece depending below the same.

It is also to be observed that it is at times necessary to call the attention of the operator to the telephone being used by the movement of the hook, and this invention seeks to apply a tripping device to this hook without in any way interfering with the use of the hook in calling the attention of the operator, and at the same time to provide means whereby the paper is shifted over the receiver a given amount.

In the drawings in which the same numeral of reference is applied to the same portion throughout the several views, Figure 1 is a side elevation of the attachment; Fig. 2 is a front elevation of the attachment; Fig. 3 is a side elevation of the attachment looking in the opposite direction from Fig. 1; Fig. 4 is a vertical sectional view of the operating gear wheel showing the position of the spring therein; Fig. 5 is a side elevation of the operating gear wheel, a portion of the frame being broken away to show the spring contained there-

in; Fig. 6 is a vertical sectional view of the paper feeding roll; Fig. 7 is an end elevation of the paper feeding roll showing the pawl which holds the roll from operating when it has been set; Fig. 8 is an end elevation of the paper feeding roll showing the pawl which operates said roll after the shield has been removed from in front of the telephone transmitter and the holding pawl released; Fig. 9 is a side elevation of a portion of the telephone standard showing the means for releasing the paper feeding roll; Fig. 10 is a plan view of the telephone standard showing the means for releasing the paper feeding roll; Fig. 11 is a side elevation of the attachment in place upon the telephone transmitter, showing a portion of said transmitter and standard; Fig. 12 is a plan view of the bracket used for holding the releasing cord; Fig. 13 is a side elevation of the bracket for holding the releasing cord; Fig. 14 is a side elevation of the apparatus with a slightly modified form of operating means; Fig. 14^a is a front view in elevation of the paper tension spring which also serves as a spring to place the proper amount of tension on the paper as it is passing under the feed roller, portions thereof being broken away to shorten the figure; Fig. 15 is a view of the fork which passes over the upper end of the telephone standard; and Fig. 16 is a view of the clamp used to secure the operating spring to the telephone standard.

The numeral 1 represents the base of the paper holding apparatus over which extend forwardly four ears 2, 3, 4 and 5. The base 1 is provided with a central opening 6 which may be placed over the opening in the head 95 of the ordinary desk telephone, the mouth piece holding said base in place as illustrated in Fig. 11. The two lower ears 2 and 3 support a small roller 7 which has one end thereof projecting beyond the ears as shown 100 at 8, for an object to be explained later. In the rear of this small roller 7 is a large roller 9 also journaled in the same pair of ears, screws 10 and 11 being screwed into the journal 9' thereof in place, and preventing the spreading of said ears 2 and 3.

Below the large roller 9 is pivoted a pressure plate 12, said plate being pivotally secured to the ears 2 and 3 by means of a small rod 13. This plate 12 has upwardly 110 extending ears 14 at each end thereof, and each ear is provided with a finger 15 upon

which bear the ends of a spring 16. This pressure plate bears upon the roller with sufficient pressure to prevent the paper from being pulled back too easily, and yet it permits the roller to slide another length of paper along when the receiver is hung up.

The large roller 9 is operated by means of a gear wheel 17 supported by a journal 18 above the journal of the large roller. This gear is provided with a spring 19 which tends to rotate the same in the opposite direction from the movement thereof by the lever 20 secured to the journal of said gear. This lever is prevented from moving more than a given distance by means of a stop 21 adjacent said gear, and by means of the finger hold 22 at the lower end of the plate 2. The gear 17 is in mesh with a small gear 23 secured on the journal of the roller 9 and said journal also carries a ratchet-wheel 24 secured thereto, while the roller has a pawl 26 pivoted thereto which is held in engagement with the ratchet-wheel by means of a spring 27, also secured to the end of the roller 9. At the opposite end of the roller 9 there is a ratchet-wheel 28 secured rigidly to said roller. The ratchet-wheel is prevented from rotating when the receiver is off the hook by means of a pawl 29 pivoted to the ear 3. This pawl is held in engagement with said ratchet wheel by means of a spring 3 secured to the side plate 5 by means of a screw 31 and the pawl is prevented from moving upwardly more than a given amount by means of a small ear 32 projecting inwardly from the ear 3. This pawl 29 is provided with a small hook 34 in which one end of a cord 35 is placed. This cord passes upwardly to a small roller 36 journaled on a backwardly extending ear 37 at the top of the plate 1, and from here the cord extends downwardly and backwardly over a roller 38 journaled on an arm 39, which is secured on the top of the telephone post. This last roller has a housing 40 to prevent the cord from being easily displaced therefrom. When used in connection with the standard desk telephone instruments, the arm carrying the roller 38 is provided with an upwardly extending portion 40' in which is formed a slot 41 to receive the pivot pin of the telephone post.

It will be noted in Fig. 11 the edge of the roller 38 is in line with the axis of the pivot post of the movable piece of the telephone. The object of this is to permit the shifting of the mouth-piece in a vertical plane without altering the length of the cord. The lower end of the cord is secured to a light fork 42 which is pivoted to a securing plate 43, the latter being held firmly on the receiver hook by means of a screw 44 passing below said hook. The rear end of the fork 42 is turned upwardly as shown at 45, to prevent said fork from rising more than a

given amount. The fork is short enough so that it does not interfere with the movement of the telephone receiver hook by the fingers, and yet is long enough so that it readily engages the receiver when the same is placed upon the hook, and it then trips the pawl at the other end of the chain.

At the top of the plate 1 the ears 4 and 5 are connected by means of a round bar 46, said bar also acting as the journal for a latch 47 which holds the journal 48 of the paper roll 49 from moving longitudinally, said latch having two ears 50 which pass into a slit 51 in said journal. This latch is also provided with a finger hold 52, and in order to prevent the latch from turning entirely around, the plate 4 is provided with a stop 53.

The paper roll is prevented from turning too rapidly and freely by means of an extension 54 of the springs which bear upon the friction plate 12 at the bottom of the plate 1.

The apparatus above described is to prevent soiling the telephone mouthpiece and may be used for that purpose, but since many persons will use the telephone without changing the paper if they can conveniently do so, it becomes necessary to provide means to prevent the telephone from being used without at the same time setting the apparatus to change the paper automatically. 90 This means is the shield 55 which is pivoted on an ear 56 extending inwardly from the forwardly projecting ear 2. The shield comprises a skeleton ring 57, in which is placed a metal disk 58 for the purpose of holding a sheet of paper to carry the telephone number and instructions for the use of the sanitary device.

The disk 58 is held in place in the ring 57 by means of three small ears 59 which are bent over the edge of the disk 58. Below the pivot point 60 a shield is provided with an arm 61 having a forwardly projecting finger 62 which is engaged by a pair of inwardly projecting arms 63 on a plate 64. The plate 64 is pivoted on the same journal as the friction roller 9, and it has upwardly extending arms 65 and 66 which are engaged by an inwardly projecting pin 67 on the finger lever.

The plate 64 has an arc shaped slot 68 therein through which the extended end of the small roller 7 projects, said roller acting as a stop for the plate 64.

From the above description it will be seen that the operation of the device is as follows: The receiver being upon the hook, the pawl at the end of the cord is prevented from engaging the adjacent ratchet-wheel, and thus the spring operating on the large gear wheel is enabled to rotate the roller 9 until the finger lever reaches the stop at the upper end of its travel, and so long as the receiver is upon the hook, the shield will remain in front of the mouth piece, said 130

shield being of a metal heavy enough to prevent the user from talking into the telephone. When the receiver is removed from the hook, the cord is slackened allowing the 5 pawl to engage the ratchet wheel at that end of the roller 9. The finger lever may then be operated to remove the shield from in front of the mouth-piece. In the operation of removing the shield from before the 10 mouth-piece the roller 9 is charged with sufficient energy from the spring to rotate the same, and at the same time to pull a short length of paper from the paper feed roll.

15 When the telephone has been used a number of times, any paper hanging below may be readily detached and thrown away by being torn off across the back edge of the pressure plate, which may be serrated or sharpened in any desired manner.

20 It will be understood that while the paper used interferes with the use of the telephone in no way at all, the shield is intended to be of sufficient thickness and rigidity as to practically prevent the use of the telephone 25 without setting the apparatus to place a fresh length of paper each time the telephone is used, thus avoiding the danger of infection to subsequent users of the telephone.

30 In Fig. 14 is shown a slightly modified form of the invention. Since it might be convenient to locate the spring setting device in a place where it might be conveniently touched by the hand in picking up the telephone, the setting device shown in that figure may be used.

35 In other respects the apparatus is substantially the same as is shown in the other views. In the place of the finger operating handle at the side of the frame, the small pulley 70 is placed upon the spring journal, and a cord 73 is passed about the same and is secured thereto. This pulley has a pin 40 45 50 55 60 65 70 75 80 85 90 95 100 105 110 115 120 125 130 which acts as the means for moving the plate 64 the same as the pin on the form of the invention shown in the preceding figures, and it is provided with another pin 72 to prevent the spring from rotating it more than the finger lever is rotated in the preceding figures, said pin coming against one of the arms of the plate 64 which acts as a stop when the bottom of the slot 68 strikes the screw 8. From this pulley the cord 73 is passed upwardly to a pulley 74 on a backwardly projecting ear 75, and after passing over said pulley, the cord passes in front of the pulley 76 on an arm 77 secured to the top of the telephone post, the same as the pulley on the other side thereof. This pulley is so placed that the point of contact of the cord therewith is in line with the axis of the telephone head, thus making the distance between the upper pulley and the lower pulley substantially the same at all times.

After passing through the lower pulley the cord is connected with one end of a fork spring 77' which is secured by means of the clamp 78 to the telephone post. This spring stands normally the distance of about $\frac{3}{4}$ of an inch in front of the telephone post, and when the latter is picked up, the thumb is placed upon the spring and pushes the fork spring back, setting the paper operating mechanism and uncovering the mouthpiece.

70

75

The paper is fed through upon hanging up the receiver in the same manner as in the previous form of the invention.

Having thus described my invention what I claim as new and desire to secure by Letters Patent of the United States, is as follows:—

1. In a sanitary device for telephone transmitters, a frame adapted to be attached to a telephone, a paper roll carried thereby, means to feed a portion of paper across the mouthpiece of the telephone, a shield to prevent the use of the telephone when said paper feeding mechanism has been set, and means to remove said shield from the telephone transmitter, substantially as described.

2. In a sanitary device for telephone transmitters, a frame adapted to be attached to a telephone, a paper roll carried thereby, means to feed a portion of paper across the mouthpiece of the telephone, a shield to prevent the use of said telephone when said paper feeding mechanism has been set, and manual means for removing said shield from in front of the telephone mouthpiece and setting the paper feeding mechanism when the telephone is to be used, substantially as described.

3. In a sanitary device for telephone transmitters, a frame adapted to be attached to a telephone, a paper roll carried thereby, paper feeding mechanism adapted to carry a length of paper across the mouthpiece of the telephone, a shield to prevent the use of said telephone without setting said paper feed mechanism, means to remove said shield from in front of the mouthpiece, and means operated by the placement of the telephone receiver upon the hook supporting the same to release the paper feeding mechanism to feed a length of paper across the mouthpiece and return the shield to its position in front of the mouthpiece, substantially as described.

4. In a sanitary device for telephone transmitters, a frame adapted to be attached to a telephone, a paper roll carried thereby, paper feeding mechanism adapted to carry a length of paper across the telephone mouthpiece, a shield to prevent the use of said telephone without setting said paper feeding mechanism, manual means to remove said shield from the mouthpiece and set the paper feeding mechanism, and means operated by the placement of the receiver upon

its hook to release the paper feeding mechanism to feed a length of paper across said telephone mouthpiece and return the shield to its position in front of the same, substantially as described.

5. In a sanitary device for telephone transmitters, a frame adapted to be attached to a telephone, a paper roll carried at the upper portion of said frame, a paper feeding roll at the lower portion of said frame and adapted to feed a length of paper across the telephone mouthpiece, a pivoted shield to prevent the use of said telephone without setting the paper feeding mechanism, and 10 means to permit the feeding of said paper across the telephone mouthpiece and the return of said shield in front of the same when the user is through with said telephone, substantially as described.
- 15 6. In a sanitary device for telephone transmitters, a frame adapted to be attached to a telephone transmitter, a paper roll carried thereby, a paper feeding roll on said frame, a spring actuated gear wheel, a finger 20 lever to compress the spring in said gear and prepare said paper feeding roll for movement, a latch to release said paper

feeding roll, and a fork upon which the telephone receiver is to be placed, and means connecting said fork and the roll holding 30 latch to release the roll when the telephone receiver is to be hung up, substantially as described.

7. In a sanitary device for telephone transmitters, a frame adapted to be attached 35 to a telephone transmitter, a paper roll carried thereby a paper feeding roll carried by said frame, a pivoted shield to prevent the use of said telephone, means to set the paper feeding roll for movement and remove said 40 shield from proximity to the mouthpiece of said telephone, and means connected with the support of the telephone receiver to release the paper feed roll and feed a length of paper across the transmitter, substantially 45 as described.

In testimony whereof I have hereunto set my hand this 19th day of November A. D. 1910, in the presence of the two subscribed witnesses.

GEORGE SEXTON BENNETT.
